(57) **CLAIM**

The ornamental design for dual-axis swivel speaker mount assembly, as shown and described.

DESCRIPTION

FIG. 1 is a top perspective view of a dual-axis swivel speaker mount assembly according to the present design; FIG. 2 is a left side view of the dual-axis swivel speaker mount assembly as shown in FIG. 1; FIG. 3 is a right side view of the dual-axis swivel speaker mount assembly as shown in FIG. 1; FIG. 4 is a front view of the dual-axis swivel speaker mount assembly as shown in FIG. 1; FIG. 5 is a rear view of the dual-axis swivel speaker mount assembly as shown in FIG. 1; FIG. 6 is a top view of the dual-axis swivel speaker mount assembly as shown in FIG. 1; and, FIG. 7 is a bottom view of the dual-axis swivel speaker mount assembly as shown in FIG. 1. The broken lines shown in FIGS. 1-7 are for purposes of illustrating portions of the dual-axis swivel speaker mount assembly that form no part of the claimed design.
